UNITED STATES PATENT OFFICE

2,439,194

STAND WITH AN ADJUSTABLE RECEPTION-PLATE CAPABLE OF BEING TIPPED OVER IN EVERY DIRECTION

Heinrich Wild, Kuttigen, Switzerland, assignor to the firm Kern & Co. A. G., Aarau, Switzerland

Application January 18, 1945, Serial No. 573,419
In Switzerland September 27, 1943Section 1, Public Law 690, August 8, 1946
Patent expires September 27, 1963

4 Claims. (Cl. 248—181)

1

In order to facilitate the setting up of stands for surveying instruments and similar objects, the reception-plate carrying the instrument, located on the head of the stand, is arranged to be movable on all sides, thus allowing it to be perfectly levelled, before the instrument is fixed up. For this purpose, adjustable stand-heads with ball-and-socket joints with a spherical zone, or full spheres, have already been in use. The disadvantage of the stands hitherto used, however, consists therein that the adjustment to be effected is, relatively speaking, not sufficiently precise, besides, the stands cannot be fastened to the extent required. These disadvantages are eliminated by the object of the present invention.

The object of the present invention is a stand with an adjustable reception-plate capable of being tipped over in every direction, particularly adapted to surveying- and military instruments, whereby the reception-plate carrying the instrument is seated on the surface of a spherical zone on the head of the stand developed as a hollow body, and is provided with a rigid journal penetrating into the head of the stand, a fastening-plate being arranged on this journal beneath the head of the stand, this fastening-plate being seated on a second surface of a spherical zone on the head of the stand, whereby its spherical center coincides with the spherical center of the first mentioned surface of a spherical zone and, for the purpose of pressing the fastening-plate on to the head of the stand, and in order to block the reception-plate, a fixing-screw is attached to its journal.

The radius of the surface of the spherical zone, on which the fastening-plate is seated on the lower part of the head of the stand, is advantageously selected to be greater than the radius of the surface of the spherical zone, on which the reception-plate is positioned. Thereby, possibilities are offered to effect an easy and precise adjustment of the reception-plate, to block it firmly in every position.

In the enclosed sketch, an embodiment of the object of the invention is shown, by way of example, the illustration being an axial section.

The head of the stand developed as a hollow body is marked 1, three pedestals 2 being attached to it. This head of the stand 1 is provided, on its upper part, with an adjoined neck 3, its exterior surface being developed as a spherical zone 4, Z being the spherical center, and r the radius. On this spherical zone 4 a reception-plate 5 is positioned, this reception-

2

plate showing a roll-shaped edge 6 at its lower end, in which the appropriate surface of a spherical zone corresponding to the spherical zone 4 is to be provided. The reception-plate 5 is provided, on its lower part, in its center, with a pivot-like, rigid journal 7, which penetrates into the head of the stand 1, its adjoined neck 3 showing a break-through 8, and its bottom a break-through 9, and an axially movable fastening-plate 10 positioned outside of the head of the stand 1 is mounted on this journal. This fastening-plate 10 is seated on a spherical zone 11 provided on the lower part of the head of the stand 1, its spherical center coinciding with the spherical center Z of the spherical zone 4. The spherical zone 11, however, possesses a greater radius R . The fastening of the reception-plate 5, by means of the fastening-plate 10, is effected by a fixing-screw 12 arranged on a threaded bolt 13 of the journal 7.

When adjusting, the reception-plate 5, with its journal 7 and the fastening-plate 10 seated thereon, is turned around the common spherical center Z of both spherical zones 4 and 11. Inasmuch as the radius R of the spherical zone 11 is greater than the radius r of the spherical zone 4, on which the reception-plate 5 is seated, an increased adjusting movement of the end of the journal 7 of the reception-plate 5, with the fastening-plate 10, is attained and, thereby, possibilities of more precise adjustment in respect to the reception-plate 5 are provided.

I claim:

1. In a tripod head, the combination of a member comprising a first convexly shaped portion at one end and a second convexly shaped portion at the opposite end, said portions having a common spherical center, positioned at a point intermediate to both said portions, said member having a hole extending from one convex portion to the other, a reception member capable of supporting an apparatus of the type described and comprising a concave lower portion fitted on said first convex portion, an elongated rod rigidly fastened to the reception member, said rod having a diameter smaller than said hole, a plate member supported on said rod and comprising a concave portion fitted on said second convex portion, and clamping means for securing said plate member on the second convex portion in selected variable positions, thereby causing the reception member to be secured in a selected angular position relative to the first convex portion.
2. In a tripod head, the combination of a hol-

low member comprising a first convexly shaped spherical portion at one end and a second convexly shaped spherical portion at the opposite end, said portions having a common spherical center, positioned at a point intermediate to both said portions, each of said convex portions having an opening therein, said openings being aligned with each other and with said spherical center, a reception member capable of supporting an apparatus of the type described and comprising a concave lower portion fitted on said first convex portion, an elongated rod integral with the reception member and extended through the openings of the hollow member, said rod having a diameter smaller than said openings, a plate member supported on said rod and comprising a concave portion fitted on said second convex portion, and a screw member for pressing said plate member against the second convex portion in selected variable positions, thereby causing the reception member to be fixed in a selected position relative to the first convex portion.

3. In a tripod head, the combination of a member comprising a first convexly shaped spherical portion at one end and a second convexly shaped spherical portion at the opposite end, said portions having a common spherical center, positioned at a point intermediate to both said portions, the radius of the first convex portion being smaller than the radius of the second con-

5 vex portion, said member having a hole penetrating the member from one convex portion to the other, a reception member capable of supporting an apparatus of the type described and comprising a concave lower portion fitted on said first convex portion, an elongated rod rigidly fastened to the reception member, said rod having a diameter smaller than said hole, a plate member supported on said rod and comprising a concave portion fitted on said second convex portion, and clamping means for securing said plate member on the second convex portion in selected variable positions, thereby causing the reception member to be secured in a selected convex position relative to the first convex portion.

10 4. A tripod head as described in claim 3, wherein said clamping means comprises a screw member threaded on said rod for pressing the plate member against the second convex portion.
